ABSTRACT

A hanger spacer tape device having a flexible elongated body and a plurality of bumps or protrusions formed on one side thereof. The hanger spacer tape device allows hangers to be spaced at intervals and stay aligned to provide effective and efficient organization of hangers and can be coiled onto itself.

FIG. 2B

FIG. 2C

FIG. 3A

FIG. 3B

HANGER SPACER TAPE**CROSS-REFERENCE TO RELATED APPLICATION**

This application is a continuation of U.S. Non-Provisional application Ser. No. 16/051,438, filed on Jul. 31, 2018, the disclosure of which, including any materials incorporated by reference therein, are incorporated herein by reference in its entirety.

BACKGROUND OF THE INVENTION

The present invention generally relates to a hanger spacer device, more particularly to a hanger spacer tape device that can adhesively attach to a closet rod or pole. The hanger spacer tape is provided with a plurality of bumps or protrusions spaced at predetermined intervals allowing hangers to be spaced according to the predetermined spacing of the bumps or protrusions.

15 Closet organization has been a challenge to many, namely, to keep one's closet neat and organized so that articles of clothing can be readily found. One issue stems from the fact that there are many types of hangers that are available to consumers, such as wire, plastic and wooden with metal hook portions, to name a few. But even with the use of the same (or similar) hangers, a closet can oftentimes appear disorganized. Articles or clothing are necessarily shifted around, making the closet appear untidy, leaving items difficult to find. Organization of hanging items, however, is not necessarily unique to personal closets, and can also be a problem for clothing retail stores.

20 Attempts have been made to improve clothing organization, but each have notable drawbacks. Examples can be seen in U.S. Pat. Nos. 2,895,618, 4,361,241, 4,760,929, 4,960,213, 7,028,855, 9,782,040, and U.S. Patent Application Publication No. 2006/0278594, and U.S. Pat. No. D247,085, each incorporated by reference herein.

25 In contrast to the aforementioned publications, the hanger spacer device in accordance with the present invention is simple to install, has the ability to be used on a variety of surfaces and in various locations, low-profile and can be discreet. Specifically, the hanger spacer device in accordance with the present invention keeps hangers (and clothes thereon) aligned, spaced at predetermined intervals, giving the closet an overall organized, clean look. Another advantage provided by exemplary embodiments of the present invention is that one can sort and view articles of clothing without disrupting the spacing of other articles of clothing in the closet. Another advantage provided by exemplary embodiments of the present invention is that when an item is removed, the hanger remains in the same place, again, not disrupting the placement of the other items in the closet.

30 The present invention also allows users to single, double, or triple space (or more, as desired by the user) items easily thereby giving the user the ability to customize his/her closet in accordance with his/her wardrobe. For example, bulkier items such as jackets may require additional spacing. Protrusions can also be intentionally "skipped" to leave spaces to create separation between different categories of clothing, allowing for further organization of the closet. Sections can be created by skipping a series of spacing elements. Overall, the present invention allows a user of the device to customize and organize as the user sees fit. The spacing elements keep the hung items aligned, spaced evenly, and looking

organized. Moreover, the low-profile appearance of the present invention does not further clutter the look of the closet.

35 With the present invention, clothes can still be moved in either direction to allow for adjustment according to a user's desires or preferences.

The present invention allows a user to customize the length of tape being needed to fit a variety of closet spaces (or other area, not limited to closets that may require similar organization). In other words, the present invention is efficient, functional, and has the ability make any closet (or other space) appear organized.

SUMMARY OF THE INVENTION

15 A hanger spacer device for keeping hangers spaced at predetermined intervals comprising a flexible elongated main body having a length and a width, wherein the length is longer than the width, the main body portion having a top surface and a bottom surface, wherein the flexible elongated main body portion is flexible both lengthwise and widthwise.

20 The hanger spacer device also comprises a plurality of protrusions comprising adjacent pairs of protrusions formed on the top surface of the flexible elongated main body, wherein the protrusions are spaced at regular intervals.

25 The hanger spacer device also has hanger spaces formed between each adjacent pair of protrusions, wherein a hanger can be placed in each hanger space respectively.

30 The hanger spacer device an adhesive provided along the bottom surface of the flexible elongated main body, wherein the hanger spacer device is configured to be mounted to a rod. The hanger spacer device can also have an elongated main body movable between a mounting position wherein the main body can become arcuate in shape to conform to an upper surface of the rod and a storage position wherein the main body can be coiled onto itself along the length of the main body in a multilayered overlapping manner.

BRIEF DESCRIPTION OF THE DRAWINGS

35 A more complete understanding of the present invention may be obtained with reference to the Detailed Description when taken in conjunction with the accompanying Drawings.

40 FIG. 1A is a perspective view of the hanger spacer tape in accordance with one aspect of the present invention;

45 FIG. 1B is a perspective view of the hanger spacer device of FIG. 1A showing how a hanger can pivot 45 degrees on the device;

50 FIG. 2A is a top view of the hanger spacer tape of FIG. 1A and 1B;

55 FIG. 2B is a side view of the hanger spacer tape of FIG. 2A;

60 FIG. 2C is a perspective view of the hanger spacer device rolled or coiled up;

65 FIG. 3A is a top view of the hanger spacer tape in accordance with a second aspect of the present invention; and

66 FIG. 3B is a side view of the hanger spacer tape of FIG. 3A.

DETAILED DESCRIPTION OF THE INVENTION

Referring now to FIG. 1, a top view of one exemplary embodiment of the hanger spacer device 101 is shown.

Hanger spacer device **101** has a flexible elongated main body **102** with left and right edges **102a** and **102b** a top surface **103** and a bottom surface **104**. Flexible elongated main body **102** is flexible both lengthwise and widthwise such that it can readily conform to surfaces of varying shapes, such as a rod or pole as shown in FIG. 1. Flexible elongated main body **102** can be in the form of a tape. The length of flexible elongated main body **102** is greater than the width of flexible elongated main body **102**.

Formed on top surface **103** of the hanger spacer device **101** is a plurality of protrusions or bumps **105**. The protrusions or bumps **105** are generally semispherical in shape. Provided on bottom surface **104** of the hanger spacer device **101** is an adhesive **106** that allows the hanger spacer device to stay adhered to the pole or rod. Adhesive **106** can be a glue or other substance that keeps hanger spacer device in place. Adhesive **106** can be one which can adhere to a number or materials that are commonly used to construct closet rods or poles, such as wood, plastic and metal.

In the exemplary embodiment seen in FIG. 2A and 2B, protrusions or bumps **105** have a rim **107** that has a circumference or rim perpendicular to top surface **103** of hanger spacer device **101** when not adhered to a rounded pole or other rounded surface. Protrusions or bumps further have a rounded top **108**.

Each protrusion or bump has a center **109** of rounded top **108**. An ideal distance between each center **109** of the plurality of protrusions **105** has been found to be approximately $\frac{3}{4}$ inch. An ideal width of each protrusion **105** has been found to be approximately $\frac{3}{8}$ inch. An ideal space between each of a pair of plurality of protrusions has been found to be approximately $\frac{3}{8}$ inch. The specified spacing allows a variety of types of hangers (metal, plastic, wooden, etc.) that have varying widths to be placed between a pair of protrusions or bumps while maintaining adequate spacing between articles of clothing. The semispheric shape of the protrusions **105** allows hangers with the clothing to be turned so that a user can view the clothing item without disturbing other pieces. This can be seen in FIG. 1B. As the protrusions **105** do not extend to side edges **102a** and **102b** of flexible elongated main body **102**, the hangers are able to pivot at least 45 degrees. The semispherical shape of the protrusions **105** also allows a hanger to slide down into space **110** in between the protrusions in the event a user places a hanger on top of the protrusion.

Moreover, in the event that bulkier articles of clothing, such as jackets, are being hung on hanger spacer tape **101**, hangers can be placed in every other (or every third) recess between the protrusions, creating equal spacing between those articles of clothing to achieve a clean, organized appearance. The hanger spacer tape device **102** also allows hung clothing to be pushed in either direction (like an accordion) for a user to view a selected piece of hung clothing. When the selected piece is released, the remaining pieces of clothing fall back into their original positions.

The hanger spacer tape device **102** can also be rolled or coiled onto itself as can be seen in FIG. 2C.

An alternate embodiment is shown in FIGS. 3A & 3B, in which hanger spacer device **101a** has a plurality of protrusions **105a** shaped as half cylinders.

The hanger spacer tape device can also be used in other places, such as on a curtain rod or shower curtain and can be used in a number of environments outside of a household closet, such as in a garage, storage unit, attic, basement, laundry room or even a car. The hanger spacer tape device

could be particularly useful in retail stores where clothing should appear organized and visible to customers.

While other shapes (such as rectangular, square, triangles, stars, hearts, circles with flat tops and trapezoids) can be used, the embodiment described herein provides certain benefits to maximize ease of use.

The flexible elongated main body can vary in thicknesses but should maintain a thickness that allows the main body to easily form around a rounded body such as a rod or pole.

While the foregoing written description of the invention enables one of ordinary skill in the art to make and use the invention, those of ordinary skill in the art will understand and appreciate the existence of variations, combination, and equivalents of the embodiments, methods, and examples provided herein. The invention should, therefore, not be limited by the embodiments and examples disclosed here, but by all embodiments and methods within the scope and spirit of the invention as claimed.

The invention claimed is:

1. A hanger spacer device for keeping hangers spaced at predetermined intervals comprising:

a flexible elongated main body having a length and a width, wherein said length is longer than said width, said flexible elongated main body having a top surface and a bottom surface, wherein said flexible elongated main body is flexible both lengthwise and width wise; a plurality of protrusions comprising adjacent pairs of protrusions formed on said top surface of said flexible elongated main body, wherein said protrusions are spaced apart at regular intervals;

hanger spaces formed between each adjacent pair of protrusions, wherein a hanger can be placed in each hanger space respectively; and

an adhesive provided along said bottom surface of said flexible elongated main body;

wherein the hanger spacer device is configured to be mounted to a rod;

wherein the elongated main body moves between a mounting position wherein the main body is arcuate in shape to conform to an upper surface of the rod and a storage position wherein the main body is coiled onto itself along the length of the main body in a multilayered overlapping manner.

2. A hanger spacer device for keeping hangers spaced at predetermined intervals comprising:

a flexible elongated main body having a length and a width, wherein said length is longer than said width, said flexible elongated main body having a top surface and a bottom surface, wherein said flexible elongated main body is flexible both lengthwise and widthwise; a plurality of protrusions comprising adjacent pairs of protrusions formed on said top surface of said flexible elongated main body, wherein said protrusions are spaced apart at regular intervals;

hanger spaces formed between each adjacent pair of protrusions, wherein a hanger can be placed in each hanger space respectively; and

wherein the hanger spacer device is configured to be mounted to a rod;

wherein the elongated main body moves between a mounting position wherein the main body is arcuate in shape to conform to an upper surface of the rod and a storage position wherein the main body is coiled onto itself along the length of the main body in a multilayered overlapping manner.
